(57) **CLAIM**

The ornamental design for a motor shaft, as shown and described.

DESCRIPTION

FIG. 1 is a perspective view of a motor shaft;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is another perspective thereof;

FIG. 9 is an enlarged view of portion 9 shown in FIG. 1; and, FIG. 10 is an enlarged view of portion 10 shown in FIG. 8. The dashed or broken lines shown in the drawings depict portions of the motor shaft in which the design is embodied that form no part of the claimed design.

The long dash short dash broken line depicts the area from which the enlarged views on FIGS. 9 and 10 that are taken on FIGS. 1 and 8 and form no part of the claimed design.

1 Claim, 10 Drawing Sheets
